UNITED STATES PATENT OFFICE.

FRANK L. SMITH, OF MARIETTA, KANSAS.

STOVEPIPE.

SPECIFICATION forming part of Letters Patent No. 661,824, dated November 13, 1900.

Application filed August 18, 1900. Serial No. 27,341. (No model.)

To all whom it may concern:

Be it known that I, FRANK L. SMITH, a citizen of the United States, residing at Marietta, in the county of Marshall and State of Kansas, 5 have invented a new and useful Stovepipe, of which the following is a specification.

This invention relates to stovepipes, and has for one object to provide improved means for adjustably connecting stovepipe-sections 10 and to fasten them together to prevent accidental separation thereof, while at the same time permitting of the sections being disconnected to take down a pipe-line.

It is furthermore designed to adapt the 15 present device for application to ordinary stovepipes now in common use without materially altering the same beyond the provision of an opening in one end thereof.

With these and other objects in view the 20 present invention consists in the combination and arrangement of parts, as will be herein-after more fully described, shown in the accompanying drawings, and particularly pointed out in the appended claims, it being understood 25 that changes in the form, proportion, size, and minor details may be made within the scope of the claims without departing from the spirit or sacrificing any of the advantages of the invention.

30 In the drawings, Figure 1 is an elevation of adjacent stovepipe-sections connected by means of the present invention. Fig. 2 is an enlarged detail transverse sectional view taken on the line 2-2 of Fig. 1. Fig. 3 is a detail perspective view of a portion of one end of a stovepipe provided with an opening in accordance with the present invention. Fig. 4 is a plan view of a tongued strip used in fastening the stovepipe-sections. Fig. 5 is a 35 detail perspective view of a fastening-clip similar to the tongued strip and which is designed to be applied to an ordinary stovepipe. Fig. 6 is a detail sectional view taken transversely through the joint of an ordinary stove- 40 pipe and showing the fastening-clip secured within the joint.

Corresponding parts are designated by like characters of reference in all of the figures of the drawings.

45 Referring to the drawings, 1 designates an ordinary stovepipe-section having the usual joint, which is formed by folding together the

opposite edges of the sheet from which the stovepipe is made. At one end of the stovepipe and at one side of the joint thereof there 55 is provided a slot or opening 2, which extends longitudinally of the stovepipe, and an intermediate transverse slot or notch 3 intersects that edge of the slot 2 which is farther away from the stovepipe-joint, as best shown in 60 Fig. 2 of the drawings. These two slots result in a substantially T-shaped slot arranged transversely of the stovepipe and adjacent to the joint thereof.

The stovepipe is furthermore provided with 65 a tongued metallic strip 4, having spaced lateral tongues 5, as shown in Fig. 4, or adjacent tongues, which are separated from each other by means of lateral incisions, as shown in Fig. 1. The flat body portion or rear edge 70 of this strip is folded with the joint in the original manufacture so as to fixedly connect the strip therewith, with the tongues projecting laterally outward through the lateral edge of the joint, as shown in Fig. 2 of the drawings. It will of course be understood that 75 the tongues are originally pressed flat against the outer side of the stovepipe, so that the latter may be free of projections; also, the strip terminates at one end adjacent to the 80 opening 2, while its opposite end extends to the opposite end of the stovepipe-section. Moreover, the strip and the opening are located upon opposite sides of the joint.

In connecting the stovepipe-sections the 85 end of the tongued section is inserted into the adjacent end of the other section, after which the sections are twisted or turned in opposite directions upon their common axis, so as to enter one of the tongues into the opening 2, as indicated at the bottom of Fig. 1, thereby interlocking the stovepipes against 90 accidental displacement, but at the same time permitting of the sections being separated by a reverse turning thereof. Should the tongue 95 not readily enter the opening or slot, any suitable pointed instrument may be inserted through the transverse slot or notch 3, so as to enter under the free end of the tongue, whereby the latter may be pried or forced away from 100 the adjacent pipe and directed into the opening in the other pipe. It will be understood that each pipe-section is designed to have an opening at one end and a tongued strip ex-

tending from the opening to the opposite end of the pipe, so that any one of the tongues of the adjacent pipe may be inserted into the opening of the other pipe, whereby the sections may have a longitudinal adjustment for the entire length of the sections.

Any ordinary stovepipe may be provided with the present invention by making the T-shaped opening in one end thereof and inserting a short tongued strip or clip 6 into the joint of the pipe at the opposite end thereof, as shown by Figs. 5 and 6 of the drawings.

What is claimed is—

1. In a stovepipe-joint, the combination of 15 adjacent stovepipe-sections, the outer of which has a longitudinal slot provided with a notch in one edge thereof, and the inner section having a lateral tongue passing outwardly through the slot and covering the notch in 20 the edge of the latter.

2. A stovepipe-section, having an external lateral tongue at one end, and a corresponding longitudinal slot at the opposite end of the stovepipe, one edge of the slot having a lateral notch.

3. A stovepipe-section, having a longitudinal folded joint, a slot at one end of the pipe, and a tongued strip, having its back edge folded into the joint, with the tongues extending laterally therefrom and upon the exterior 30 of the pipe, the tongues and the slot being upon opposite sides of the joint.

In testimony that I claim the foregoing as my own I have hereto affixed my signature in the presence of two witnesses.

FRANK L. SMITH.
